Application March 25, 1942, Serial No. 436,128

2 Claims. (Cl. 189—56)

This invention relates to steel doors of the rolling type, and more particularly to a method of joining and maintaining the slats, of which these doors are made, in proper position and in separating them for repairs or other purposes.

A particular object of the invention is to provide a simple lock which will maintain the slats in proper relation but which may be manipulated to separate the slats when it is so desired.

In the drawing—

Fig. 1 is a plan view of a door made up of slats embodying my invention;

Fig. 2 is a cross-sectional view taken on the line 2—2 of Fig. 1;

Fig. 3 is a detail view of the locking element;

Fig. 4 is a view showing the manner in which the slats may be disengaged;

Fig. 5 is a perspective view of the locking element;

Fig. 6 is a view showing another method of separating the slats.

In the past it has been customary to make the slats 10 of metal and to bend the lateral edges thereof upon themselves to form along one longitudinal edge a grooved portion 11 and at the other longitudinal edge a tongue portion 12. A series of slats are then joined together by combining the tongue and groove portions to form the curtain or door. It was then necessary to rivet the ears on the ends of the slats to prevent them from coming apart. This required riveting on the assembly job and also prevented removal of the slats for repair or other purposes. If the slats were damaged or required replacement, it was necessary to shear off the rivets holding the locking member in place.

My invention resides in a novel locking means which will maintain the slats together in their normal position but which will allow their separation when desired. Accordingly a plate 15 is provided and is riveted at 16 to the slat 10. The plate 15 has a depending member 17 adapted to engage the plate on the next slat to prevent it from folding in more than one direction so that when the door is unrolled the slats will be kept approximately in the same plane. At the other end of the ear 15 is a stop lug 18 bent at right angles to the plate and positioned adjacent the groove 11, as is best shown in Fig. 5. The depending member 17 forms a wearing surface for the lug 18 and prevents excess drafts around the ends of the slats.

In the normal operation and in the normal positions the lug 18 engages the edge 19 of the

tongue member 12 and thus prevents endwise movement of the slats of the door when unrolled or in the rolled state. However, the slats may be separated by folding them beyond the normal folding position so that the edge 19 of the tongue portion uncovers the lug 18, as shown in Fig. 4. The slats may then be slid endwise to disengage the tongue and groove members.

When the slats are slid endways until the locks are disengaged, the slats themselves are in proper position to disengage and they may be sprung apart by moving one slat a short distance, as shown in Fig. 6. Thus it is possible to assemble the door or curtain where a clearance of only a few inches exists on either end.

It will be appreciated that with this structure all repairing may be done in the factory and the door or curtain assembled with very little manipulation on the job.

20 I claim:

1. The combination with a rolling door consisting of slats joined by means permitting pivotal angular movement and endwise movement, of devices secured to the ends respectively of said slats, lugs on said devices to prevent endwise movement of the slats with respect to each other when the door is unrolled, said devices having outwardly bent depending members each of which is engageable with the next adjacent one 25 of said devices to limit pivotal movement of the slats in one direction to a relation in which they are disposed approximately in the same plane while the door is unrolled.

2. An end lock device for use in conjunction 30 with rolling door slats joined by means permitting pivotal angular movement and endwise movement of the slats with respect to each other, said devices comprising a plate having provision for securing the device to one slat, a stop lug 35 integral with said plate and disposed at an angle with respect thereto, said lug serving to confront the adjacent end of an adjoining slat to prevent endwise movement of said slats, said lug being brought to a position clear of said adjacent end 40 when the slats are in a predetermined angularly disposed relation, so that the slats may be moved endwise to separate the same, and a depending member integral with said plate to cooperate with 45 a companion end lock device on an adjoining slat next below to limit the pivotal movement of said slats in one direction to a relation in which they are disposed approximately in the same plane.

ELLIS G. ANDERSON.
